REFRIGERATED CABINET WITH HEAT TRANSFER MEANS ON INNER LINER OF THE DOOR

William G. Spiegelhalter, Erie, Pa., assignor to
General Electric Company, a corporation of
New York

Application December 30, 1952, Serial No. 328,727

12 Claims. (Cl. 62—99)

1

My invention relates to refrigerated cabinets and more particularly to such cabinets including refrigerated liners.

In many refrigerated cabinets, for example, chest type food freezers, it is customary to provide an inner liner the top of which is a substantial distance below the top of the outer case. The outer case and the inner liner are then connected in this region by a downwardly and inwardly inclined breaker strip. It is common to refrigerate such cabinets by a refrigerating coil or other means secured to the exterior surface of the inner liner. It can be seen, therefore, that since the top of the inner liner is disposed below the top of the outer case, it is impossible for the top of the refrigerating coil to extend entirely to the top of the food storage compartment. Accordingly, the area of the food storage compartment above the top of the inner liner and adjacent the inner wall of the lid may tend to run at a higher temperature than is desirable for the proper storage, for example, of frozen foods. In accordance with my invention an arrangement is provided for removing heat from this region of the food storage compartment above the level of the top of the inner liner.

Accordingly, it is an object of my invention to provide an improved refrigerated cabinet including an improved arrangement for securing more nearly uniform temperatures throughout the storage compartment.

It is another object of my invention to provide an improved refrigerated cabinet of the chest type including an improved arrangement for cooling air in the region of the top of the food storage compartment.

Further objects and advantages of my invention will become apparent as the following description proceeds and the features of novelty which characterize my invention will be pointed out with particularity in the claims annexed to and forming part of this specification.

In carrying out the objects of my invention, an auxiliary member of heat-conducting material is resiliently mounted on the inner wall of the lid or door and is arranged to engage the refrigerated liner so that heat is transferred to the refrigerated liner from the region adjacent the inner wall of the lid or door through this auxiliary member. Arrangements may also be provided for minimizing any tendency of the auxiliary member to adhere to the inner liner as a result of frost formation.

For a better understanding of my invention, reference may be had to the accompanying draw-

2

ings in which Fig. 1 is a sectional elevation view of a portion of a refrigerated cabinet illustrating one embodiment of my invention.

Fig. 2 is a sectional elevation view of a portion of a refrigerated cabinet showing another embodiment of my invention.

Fig. 3 is a sectional elevation view of a portion of a refrigerated cabinet showing still another modified form of my invention.

Fig. 4 is a sectional elevation view of a portion of a refrigerated cabinet showing a further modified form of my invention.

Fig. 5 is a sectional elevation view of a portion of a refrigerated cabinet showing still another modified form of my invention.

Referring to Fig. 1 there is shown a refrigerated cabinet or freezer including an outer case 1 and an inner liner 2 spaced from the outer case and generally defining a food storage compartment 3.

20 The space between the outer case and the inner liner is filled with a suitable heat-insulating material 4. The space between the outer case and the inner liner adjacent the access opening of the food storage compartment is closed by a breaker strip 5. As shown in Fig. 1 the top of the inner liner 2 is located a substantial distance below the top of the outer case 1 and the breaker strip 5 connecting the outer case and the inner liner is accordingly inclined downwardly and inwardly as shown.

25 The breaker strip 5 may be connected to the outer case and inner liner in any suitable manner, as by screws 6. The access opening, which is located at the top of the food storage compartment 3, is closed by a lid or closure member 7, which is mounted by a hinge 8 on the outer case 1. The lid 7 includes an outer wall 7' and a spaced inner wall 9, the space between these walls being filled with a suitable heat-insulating material 10. A breaker strip 10a closes

30 the gap between the walls 7' and 9 adjacent the access opening.

35 The food storage compartment 3 is refrigerated in a conventional manner by a refrigerant-conducting conduit 11 which is secured to the exterior surface of the inner liner 2 in any suitable manner, as by brazing thereto. The conduit 11 may extend over substantially the entire exterior surface of the inner liner 2 providing a more or less uniform cooling within the confines of the liner 2. However, the top of the inner liner is located a substantial distance below the top of the outer case and below the inner wall 9 of the lid; hence it is a substantial distance be-

40 low the top of the space available within the cabinet for the storage of food. This space, for

45

45

50

55

example in the region indicated by 12, above the top of the inner liner 2 and below the inner wall 9 of the lid 7 may therefore be at a temperature which is too high for proper storage of frozen food over a long period.

In accordance with my invention, an arrangement is provided for transferring heat from the region 12 to the inner liner 2 and hence to the refrigerant-conducting conduit 11, thereby achieving a more nearly uniform temperature throughout the food storage compartment defined by the inner liner 2 and the lid 7. To accomplish this result a sheet or member 13, which is made of a material of good thermal conductivity, for example, aluminum, is mounted on the inner wall 9 of the lid 7. This member 13 is arranged to have its edge or perimeter 14 engage the inner liner 2. To facilitate this engagement, the inner liner 2 is formed to provide a shoulder 15 at the top edge thereof and the edge 14 of the member 13 engages this shoulder 15.

In order to provide for a better contact between the member 13 and the shoulder 15, the member 13 is resiliently urged downwardly against the shoulder 15 when the lid 7 is in its closed position. This is accomplished by providing a plurality of springs 16 between the inner wall 9 of the lid 7 and the member 13. These springs are of the coil type and each surrounds a corresponding rivet or rod 17 employed for mounting the member 13 on the inner wall 9. Each rod 17 includes heads at each end for holding the member in mounted position on the inner wall. The rods 17 having a sliding fit with openings in either the inner wall 9 or the member 13 to provide for movement of the member 13 relative to the lid. Moreover, as shown, the plurality of rods 17 and springs 16 are arranged in spaced relationship throughout the area of the inner wall of the lid so as to provide a universal mounting whereby the member 13 may adapt itself to engagement with the liner 2 throughout the extent of the shoulder 15 despite variation from an exact parallel mounting of these members.

By the use of the member 13, heat from the region 12 is readily conducted along the heat-conducting material of the member 13 and directly to the refrigerated inner liner 2 from which it is dissipated to the refrigerant flowing through the conduit 11. In this way the temperatures in the region 12 are kept below that desired for proper preservation of frozen food over a prolonged period and the temperatures throughout the storage compartment 3 are maintained more nearly uniform. Moreover, the member 13 extends across the inner end of the air gap 17a between the lid and the cabinet so that heat leakage through this gap is removed and transferred to the inner liner before it can reach the food stored in the compartment 3.

A modified form of my invention is shown in Fig. 2. Improved thermal insulation makes possible the use of thinner walls, that is, walls having a shorter distance between the outer case and the inner liner. However, in order to minimize edge losses between the outer case and the inner liner it is still necessary to employ a breaker strip having substantially the same width as that employed with thicker walls. In order to obtain this necessary width of breaker strip with thinner walls it is necessary that the breaker strip be inclined downwardly toward a more nearly vertical position. This causes the top of the inner liner to be even further below the top of the outer case in the form shown in Fig. 2, leav-

ing a region 18 between the top of the inner liner and the lid which is even larger than the region 12 in the form shown in Fig. 1. The heat-conducting auxiliary member 19, which corresponds to the member 13 in the form of Fig. 1, is therefore even more advantageous in the embodiment shown in Fig. 2 since the problem of the warmer region 18 is of greater magnitude.

As in the form shown in Fig. 1 the inner liner 2 is provided with a shoulder 20 which is engaged by the flanged edge portion 21 of the heat-conducting member 19. The member 19 is mounted on the inner wall of the lid 22 by a plurality of rods, one of which is shown at 23, and springs, 15 one of which is shown at 24. To provide an air gap between the lid and the storage cabinet of sufficient length the lid is formed to include a depending portion adjacent the perimeter thereof. This depending portion extends, as 20 shown, downwardly generally parallel to the steeply inclined breaker strip 26. In the form of invention shown in Fig. 2 the member 19 is shaped to conform closely to the shape of the depending portion 25 and for this purpose includes 25 a circumferential depending portion 27.

In the form of invention shown in Fig. 1 the member 13 is shown extending throughout the area of the inner wall of the lid. In some circumstances at least it may not be necessary to utilize 30 a heat-conducting member extending throughout this area. In Fig. 3 there is shown a modified form of my invention in which the heat-conducting auxiliary member 28 is formed with a large central aperture 29 and hence extends only in a 35 general region of the circumferential area of the lid 30. The member 28 may conveniently be referred to as an annulus of rectangular shape, being formed of a continuous sheet extending generally adjacent the perimeter of the rectangular shaped lid 30. As in the form of invention 40 previously described, the heat-conducting member 28, which may be formed from sheet aluminum, for example, is mounted on the inner wall 31 of the lid 30 by rods or rivets, one of which 45 is shown at 32 and biasing springs, one of which is shown at 33. The member 28 includes at its outer edge a flanged portion 34 which is urged by the springs 33 into direct heat exchange with the shoulder 35 formed at the upper edge of the 50 liner 2. The liner 2, as in the forms previously described, is refrigerated by a refrigerant-conducting conduit, the top pass of which is shown at 11. The auxiliary member 28 transfers heat from the region 36 between the lid 30 and the 55 top of the liner 2 in the same manner as described in connection with the form of invention shown in Fig. 1.

In the forms of invention shown in Figs. 1, 2 and 3 it is possible that under some circumstances 60 there might be a tendency for the heat-conducting member to adhere to the shoulder of the liner because of frost formed on the liner by the proximity of the refrigerant-conducting conduit 11 to this region. In Figs. 4 and 5 there are shown 65 modified forms of my invention for minimizing this problem. In Fig. 4 the inner liner 37 is shaped to provide a shoulder 38 which is spaced outwardly from the wall defining the food storage compartment and which is therefore somewhat remote from the refrigerant-conducting conduit 11. An auxiliary member 39 of heat-conducting material is mounted in the same manner as in the forms of invention previously described and it includes a circumferential flanged 70 portion 40, which, in the closed position of the lid,

is brought into engagement with the shoulder 38 of the liner 37. However, since this shoulder 38, as mentioned above, is somewhat remote from the conduit 11 it will be at a slightly higher temperature than the remainder of the inner liner 37. While this difference is slight it is sufficient to cause the frost to form on or migrate to the region more immediately adjacent the refrigerant-conducting conduit 11. Accordingly, the shoulder 38 of the liner is substantially free of frost formation, and any tendency of the auxiliary member 39 to adhere thereto is minimized.

Another arrangement for minimizing the tendency of the auxiliary heat-conducting member to adhere to the liner is shown in Fig. 5. In this form of my invention the liner 41 is shaped to omit the shoulders shown in the previous forms of this invention. Instead the liner 41 is curved at its upper end as shown at 42. The auxiliary heat-conducting member 43 in this form of my invention is mounted on the lid in the same manner as in the forms of invention previously described. However, in lieu of being formed at a circumferential edge with a horizontally extending flanged portion as in the previous forms of my invention, the heat-conducting member 43 is curved to its edge, as indicated at 44. The member 43 is formed of a relatively resilient heat-conducting sheet material, such as aluminum or steel, so that the edge may be forced inwardly by engagement with the curved portion 42 of the inner liner during the closing of the lid and will spring outwardly to its original position when the lid is opened. The member 43 may initially engage the inner liner in the region indicated by the dotted lines 45 and the edge 44 thereafter rides along the inner liner to the final position shown by the solid lines in Fig. 5. In so riding along the inner liner the member 43 scrapes therefrom any frost which may have formed thereon. Accordingly, each time the lid is closed any frost formed on the liner in the region of engagement by the heat-conducting member is removed by scraping. Hence this frost is kept to a minimum, thereby minimizing any tendency for the member 43 to adhere to the inner liner because of frost in this region.

While I have shown and described specific embodiments of my invention, other applications will readily occur to those skilled in the art. For example, while my invention has been described in connection with a chest-type freezer and has particular advantages in such a cabinet because of the location of the colder and warmer regions of air therein, it will be apparent that the construction could also be applied to upright cabinets. The construction in such a case would be the same as if Fig. 1 were regarded as a sectional plan view instead of a sectional elevation view as described previously. This application to upright cabinets may be of increasing significance as doors on such cabinets become thinner and more deeply recessed and hence as the inner wall thereof is disposed at an increasing distance from the refrigerated liner. Accordingly, I do not desire my invention to be limited to the particular constructions shown and described and I intend by the appended claims to cover all modifications within the spirit and scope of my invention.

What I claim as new and desire to secure by Letters Patent of the United States is:

1. In a refrigerated cabinet an outer case, an inner liner spaced from said outer case and de-

fining a food storage compartment having an access opening, a closure member hinged to said outer case and adapted to close said access opening, means secured to said liner for refrigerating said storage compartment, said closure member including an inner wall defining one wall of said storage compartment and disposed in spaced relationship to said liner whereby said refrigerating means does not extend entirely to the region 10 adjacent said inner wall of said closure member, an auxiliary member of heat-conducting material mounted on said inner wall of said closure member, said auxiliary member being arranged to engage said refrigerated inner liner when said closure member is in its closed position for cooling the region of said storage compartment beyond said inner liner and adjacent said inner wall of said closure member.

2. In a refrigerated cabinet of the chest type, 20 an outer case, an inner liner spaced from said outer case and defining a food storage compartment having an access opening at the top thereof, a lid hinged to said outer case and adapted to close said access opening, means secured to said liner for refrigerating said storage compartment, said lid including an inner wall defining the top of said storage compartment and disposed above the top of said liner whereby said refrigerating means does not extend entirely 30 to the top region of said storage compartment, and an auxiliary member of heat-conducting material mounted on said inner wall of said lid, said member being arranged to engage said refrigerated inner liner when said lid is in its closed position for cooling the region of said storage compartment above the level of the top of said liner.

3. In a refrigerated cabinet an outer case, an inner liner spaced from said outer case and defining a food storage compartment having an access opening, a closure member hinged to said outer case and adapted to close said access opening, means secured to said liner for refrigerating said storage compartment, said closure member including an inner wall defining one wall of said storage compartment and disposed in spaced relationship to said liner whereby said refrigerating means does not extend entirely to the region 40 adjacent said inner wall of said closure member, an auxiliary member of heat conducting material mounted on said inner wall of said closure member, said auxiliary member being resiliently urged into engagement with said refrigerated inner liner when said closure member is in its closed position for cooling the region of said storage compartment beyond said inner liner and adjacent said inner wall of said closure member.

4. In a refrigerated cabinet of the chest type, 60 an outer case, an inner liner spaced from said outer case and defining a food storage compartment having an access opening at the top thereof, a lid hinged to said outer case and adapted to close said access opening, means secured to said liner for refrigerating said storage compartment, said lid including an inner wall defining the top of said storage compartment and disposed above the top of said liner whereby said refrigerating means does not extend entirely to the top region of said storage compartment, an auxiliary member of heat-conducting material mounted on said inner wall of said lid, said member being resiliently urged into engagement with said refrigerated liner when said lid is in its closed position 70 for cooling the region of said storage compartment above the level of the top of said liner.

5. In a refrigerated cabinet of the chest type, an outer case, an inner liner spaced from said outer case and defining a food storage compartment having an access opening at the top thereof, a lid hinged to said outer case and adapted to close said access opening, means secured to said liner for refrigerating said storage compartment, said lid including an inner wall defining the top of said storage compartment and disposed above the top of said liner whereby said refrigerating means does not extend entirely to the top region of said storage compartment, an auxiliary member of heat-conducting material mounted on said inner wall of said lid, said member being arranged to engage said refrigerated inner liner when said lid is in its closed position for cooling the region of said storage compartment above the level of the top of said liner, and a plurality of springs between said inner wall of said lid and said member for resiliently urging said member into engagement with said liner, said springs being arranged in spaced relation for providing a universal mounting for said member relative to said lid and said liner.

6. In a refrigerated cabinet of the chest type, an outer case, an inner liner spaced from said outer case and defining a food storage compartment having an access opening at the top thereof, a lid hinged to said outer case and adapted to close said access opening, means secured to said liner for refrigerating said storage compartment, said lid including an inner liner defining the top of said storage compartment and disposed above the top of said liner whereby said refrigerating means does not extend entirely to the top region of said storage compartment, said liner being formed to provide a horizontally extending shoulder adjacent the top edge thereof, an auxiliary member of heat-conducting material mounted on the inner wall of said lid, said member being arranged to engage said shoulder of said refrigerated liner when said lid is in its closed position for cooling the region of said storage compartment above the level of the top of said liner.

7. In a refrigerated cabinet of the chest type, an outer case, an inner liner spaced from said outer case and defining a food storage compartment having an access opening at the top thereof, a lid hinged to said outer case and adapted to close said access opening, means secured to said liner for refrigerating said storage compartment, said lid including an inner liner defining the top of said storage compartment and disposed above the top of said liner whereby said refrigerating means does not extend entirely to the top region of said storage compartment, said liner being formed to provide a horizontally extending shoulder adjacent the top edge thereof, an auxiliary member of heat-conducting material mounted on the inner wall of said lid, said member being arranged to engage said shoulder of said refrigerated liner when said lid is in its closed position for cooling the region of said storage compartment above the level of the top of said liner, and a plurality of springs between said inner wall of said lid and said member for resiliently urging said member into engagement with said liner, said springs being arranged in spaced relationship for providing a universal mounting for said member relative to said lid and said liner.

8. In a refrigerated compartment of the chest type, an outer case, an inner liner spaced from said outer case and defining a food storage com-

partment having an access opening at the top thereof, the top of said liner being lower than the top of said outer case, a downwardly and inwardly inclined breaker strip for closing the space between said outer case and said inner liner adjacent said access opening, a lid hinged to said outer case and adapted to close said access opening, means secured to said liner for refrigerating said storage compartment whereby said refrigerating means does not extend entirely to the top region of said storage compartment, an auxiliary member of heat-conducting material mounted on the inner wall of said lid, said member being arranged to engage said refrigerated liner when said lid is in its closed position for cooling the region of said storage compartment above the level of said liner.

9. In a refrigerated cabinet of the chest type, an outer case, an inner liner spaced from said outer case and defining a food storage compartment having an access opening at the top thereof, a lid hinged to said outer case and adapted to close said access opening, means secured to said liner for refrigerating said storage compartment, said lid including an inner wall defining the top of said storage compartment and disposed above the top of said liner whereby said refrigerating means does not extend entirely to the top region of said storage compartment, and an auxiliary member of heat-conducting material mounted on said inner wall of said lid, said auxiliary member comprising a sheet of heat-conducting material formed to provide a peripheral portion having a large central aperture, the edge of said peripheral portion being arranged to engage said inner liner when said lid is in its closed position for cooling the region of said storage compartment above the level of the top of said liner.

10. In a refrigerated compartment of the chest type, an outer case, an inner liner spaced from said outer case and defining a food storage compartment having an access opening at the top thereof, the top of said liner being lower than the top of said outer case, a downwardly and inwardly inclined breaker strip for closing the space between said outer case and said inner liner adjacent said access opening, means secured to said liner for refrigerating said storage compartment whereby said refrigerating means does not extend entirely to the top region of said storage compartment, said liner being formed to provide a horizontally extending shoulder adjacent the top edge thereof, a lid hinged to said outer case and adapted to close said access opening, said lid including a depending peripheral portion having a large central aperture, the edge of said peripheral portion being arranged to engage said inner liner when said lid is in its closed position for cooling the region of said storage compartment above the level of the top of said liner.

11. In a refrigerated cabinet of the chest type, an outer case, an inner liner spaced from said outer case and defining a food storage compartment having an access opening at the top thereof, a lid hinged to said outer case and adapted to close said access opening, said liner including a vertical portion, means secured to said vertical

10 portion having an access opening at the top thereof, the top of said liner being lower than the top of said outer case, a downwardly and inwardly inclined breaker strip for closing the space between said outer case and said inner liner adjacent said access opening, a lid hinged to said outer case and adapted to close said access opening, means secured to said liner for refrigerating said storage compartment whereby said refrigerating means does not extend entirely to the top region of said storage compartment, an auxiliary member of heat-conducting material mounted on the inner wall of said lid, said member being arranged to engage said refrigerated liner when said lid is in its closed position for cooling the region of said storage compartment above the level of said liner.

75

portion of said liner for cooling said storage compartment, said liner further including a shoulder spaced outwardly from said vertical portion and hence from said cooling means whereby frost forms on said vertical portion of said liner in preference to said shoulder, said lid including an inner wall defining the top of said storage compartment and disposed above the top of said liner whereby said cooling means does not extend entirely to the top of said storage compartment, and an auxiliary member of heat-conducting material mounted on said inner wall of said lid, said member being arranged to engage said shoulder of said liner when said lid is in its closed position for cooling the region of said storage compartment above the level of the top of said liner.

12. In a refrigerated cabinet of the chest type, an outer case, an inner liner spaced from said outer case and defining a food storage compartment having an access opening at the top thereof, a lid hinged to said outer case and adapted to close said access opening, means secured to said liner for refrigerating said storage compartment, said lid including an inner wall defining the top of said storage compartment and disposed above the top of said liner whereby said refrigerating means does not extend entirely to

the top region of said storage compartment, the upper edge of said liner being curved outwardly to provide a flaring mouth, and an auxiliary member of resilient heat-conducting material including a downwardly depending peripheral portion, the edge of said peripheral portion being arranged to engage said curved portion of said liner as said lid is moved to its closed position, said edge riding along said curved upper edge of said liner in resilient engagement therewith during the final closing movement of said lid for scraping any frost from said liner in the region engaged by said auxiliary member, said heat-conducting auxiliary member providing for heat transfer from the region of said storage compartment above the level of the top of said liner.
